THERMOSTATICALLY CONTROLLED SAFETY PILOT BURNER AND SWITCH DEVICE FOR BURNER SYSTEMS

Leo Kathe, Cleveland, Ohio

Application November 29, 1946, Serial No. 713,184

6 Claims. (Cl. 158—117.1)

1

This invention relates to improvements in a safety pilot.

An object of the present invention is to provide in combination with a pilot having a fuel flame, an elongated hood adapted to protect the flame from being extinguished, and to direct the flame to the burner, together with an operating arm parallel to the hood and rigidly connected with a free end of the hood, in combination with a control member adjacent the operating arm 10 whereby expansion and contraction of the hood moves the operating arm relative to the control device.

Another object of the present invention is to provide the above described combination wherein the hood is of channel form adapted to protect the flame, and special means is provided for controlling the heating of the hood by the pilot flame when the latter is relatively low.

My invention also contemplates the construction of the hood and operating arm of material having substantially similar coefficients of expansion and of approximately equal length so that they are substantially equally affected by changes in ambient temperature.

My invention also contemplates the combination of the preceding paragraph wherein the control member is an electrical switch of the type operable upon movement of the order of a few thousandths of an inch and wherein the switch and the fixed end of the hood have a common mounting means whereby a very fine control is obtained, as will be later described.

Other objects and advantages of my invention will be apparent from the accompanying drawings and description, and the essential features thereof will be set forth in the appended claims.

In the drawings,

Fig. 1 is a side elevational view of one embodiment of my device, parts being broken away to more clearly show the construction;

Fig. 2 is a bottom plan view of the same;

Figs. 3 and 4 are sectional views taken along similarly numbered lines of Fig. 1; while

Fig. 5 is a diagrammatic view showing schematically one use of my device in a fuel control system.

Without in any way limiting myself to the specific form shown in the various views, I have disclosed a main burner 10 and pilot means 11 for lighting the same which is connected at 12 with a source of combustible fuel. The pilot is mounted in a block 13 which is rigidly secured in one end of the hood 14 which is of elongated channel form having an upper web 14a and down-turned flanges 55

2

14b so that the pilot flame is protected against accidental extinguishing by being blown out and the pilot flame is directed to burner 10. The right-hand end of the hood 14, as viewed in Figs. 1 and 2, is fixed to bracket means 15. The left-hand end is free and positioned adjacent the burner 10 so that the pilot flame issuing from the left-hand end of the hood lights the fuel issuing from the burner. The channel 14 is of a material adapted to contract and expand under the influence of the pilot flame for a thermostatic control purpose, as will presently appear. Rigidly secured to the free end of the hood 14 is an operating arm 16. The securing means here shown comprises a V-shape band 17 welded or otherwise secured to the hood 14 and the arm 16. The free end of the arm 16, moving unrestrained in the opening 15a of the bracket 15, is adapted to engage the operator 18 of an electrical switch 19 which is preferably mounted in the bracket 15. Obviously, any control device, either mechanical or electrical, might be so positioned to be engageable by the arm 16 to provide a control effect upon expansion and contraction of the hood 14. For the purpose of providing a very fine control, where necessary, I have shown a switch 19 of the type adapted to be operated by movement of the member 18 a very small amount of the order of a few thousandths of an inch or less. Such a switch 30 is shown in Patent No. 1,960,020 granted May 22, 1934 to P. K. McGall, but I do not desire to be limited as to the actual switch used.

Obviously, various devices may be provided to prevent damage to the control member 19 upon over-travel of the arm 16. The specific means here shown comprises a plunger 20 held outwardly from arm 16 by means of a relatively stiff spring 21 housed in the arm. The projection 20 acts as a part of arm 16 until the operator 18 can move no farther, after which, spring 21 may be slightly compressed. This provision for over-travel is not essential to the operation of my invention, but some such provision is generally desirable.

45 Various means may be provided for controlling the adjustment of the plunger 20 with respect to the operator 18. I have here shown an adjustment which comprises the mounting of the member 16a on the arm 16 by a threaded connection, together with a lock nut 22 so that the effective length of arm 16 may be adjusted as desired. My invention is not limited to any specific form for providing the adjustment of the space between members 20 and 18.

50 One manner of using my invention is shown

schematically in Fig. 5 where valve 23 controls the flow of fuel through line 24 to burner 10. This valve is normally closed by spring 25 and is moved to open position by the solenoid 26 when the same is energized from the electrical source L1,L2. The switch 19 is of the normally closed type and is opened whenever the operator 18 is depressed. Obviously, whenever switch 19 is in its normally closed position depression of the button 27 will close the electrical circuit so as to open valve 23 to supply fuel to the burner 10.

In operation, when the hood 14 is cold, it is contracted in length and the operating arm 16 holds the member 18 depressed so that the switch 19 is open. In this position of the parts, the burner 10 cannot be supplied with fuel as there is no pilot flame to light it. When the pilot 11 is lit, the flame travels along the hood 14 issuing adjacent the burner 10 and the hood 14 is heated, causing it to expand. This draws the arm 16 toward the left, as viewed in Fig. 1, so that the plunger 20 finally releases the operator 18, whereupon switch 19 attains its normally closed position, whereupon the operator may press the button 27 so as to energize solenoid 26 causing opening of valve 23 and the supply of fuel through line 24 to the burner 10 where the fuel is ignited by the flame issuing from the hood 14.

It will be noted that the operating arm 16 is below the hood 14 in a position where it receives very little heat from the pilot flame.

A satisfactory device is provided where the hood 14 is of material which expands and contracts under the influence of the pilot flame while the operating arm 16 is of material whose length is relatively unaffected by heat, such as Invar.

There are special cases where a very fine adjustment is desired between the members 20 and 18 and this is particularly difficult where the safety pilot device is subject to ambient temperatures which vary widely. In such cases, I find it advisable to make the hood 14 and the arm 16 of materials of substantially the same coefficient of expansion. For instance, I have made them both of stainless steel with very good results. Utilizing this construction, if the ambient temperature should increase considerably, the hood 14 will expand and, since the right-hand end is fixed, as viewed in Fig. 1, the left-hand end will move toward the left carrying the band 17 and the end of arm 16 in the same direction. However, the arm 16 being of substantially the same length as the hood 14, and parallel thereto, will expand a substantially equal amount so that the end of the plunger 20 will remain in substantially the same absolute position relative to the switch operator 18. When the switch and the hood 14 are fastened to the same rigid body, as for instance the bracket 15, this setting may be held within extremely narrow limits. It will thus be seen that using this construction and using a micro-switch at 19, I have provided a control which is much finer than others known to me.

An improvement which may be used to obtain a still finer control is illustrated in Fig. 1, where the hole 14c is provided in the upper wall 14a of the channel-shaped hood, whereby an escape-ment of hot gases will provide a greater heat loss, thus producing a contraction of the channel 14 sufficient to shut off gas supply to burner 10 at gas pressures as high as one and eight-tenths inches of water pressure.

My safety pilot, however, provides an ignitable flame from the open end of channel 14 at extremely low gas pressures, even after the chan-

nel has contracted to a point where gas can not be supplied to burner 10. This device will provide sufficient flame to ignite burner 10 at pressures as low as two-tenths of one inch water pressure. In other words, my device can be set to prevent gas supply to burner 10 when gas pressure drops below 1.8 inches water gage although the pilot flame is still available at the open end of channel 14 until gas pressure drops below 0.2 inch water gage. This provides a wide margin of safety.

What I claim is:

1. Safety pilot construction comprising an elongated generally horizontal hood having fixed and free ends, pilot means communicating with one end thereof for heating said hood, an elongated operating arm generally parallel to said hood and having one end fixed to the free end of said hood, said arm being relatively unaffected by the heat of said pilot means, said arm and said hood being substantially straight in both heated and cooled condition, a control member adjacent the other end of said arm and adapted to be operated thereby responsive to elongation and contraction of

said hood under influence of said pilot means, and said hood and arm having closely similar coefficients of expansion and being of approximately equal length whereby they vary similarly in length responsive to ambient temperatures.

2. Safety pilot construction comprising an elongated generally horizontal hood having fixed and free ends, pilot means communicating with one end thereof for heating said hood, an elongated operating arm generally parallel to said hood and having one end fixed to the free end of said hood, said arm being relatively unaffected by the heat of said pilot means, said arm and said hood being substantially straight in both heated and cooled condition, an electrical switch adjacent the other end of said arm and adapted to be operated by contraction of said hood when said pilot means is not heating.

3. Safety pilot construction comprising an elongated generally horizontal hood having fixed and free ends, pilot means communicating with one end thereof for heating said hood, an elongated operating arm generally parallel to said hood and having one end fixed to the free end of said hood, said arm being relatively unaffected by the heat of said pilot means, said arm and said hood being substantially straight in both heated and cooled condition, an electrical switch adjacent the other end of said arm and adapted to be operated by contraction of said hood when said pilot means is heating at a low rate.

4. Safety pilot construction comprising an elongated generally horizontal channel, said channel being of material expandable when heated, said channel having one end fixed and the other end free, a main burner adjacent the free end of said channel, pilot means providing a flame within said channel adapted to travel from the fixed end toward the free end thereof, an elongated operating arm generally parallel to said channel and having one end fixed to the free end of said channel, said arm and said channel being substantially straight in both heated and cooled condition, and a control member adjacent the other end of said arm and adapted to be operated thereby responsive to elongation and contraction of said channel under influence of said flame, whereby said channel protects said flame from being extinguished while acting as a thermostatic control member and said channel provides means for conducting said pilot flame to said main burner.

5. The combination of claim 4 wherein a hole is provided through the top wall of said channel intermediate its ends in position to pass a portion of the heat of said pilot flame through the top wall of said channel, whereby to reduce the heating effect of a flame upon said channel so that the latter will contract and operate said control member while pilot flame is still available adjacent said main burner.

6. Safety pilot construction comprising an elongated generally horizontal hood having fixed and free ends, pilot means communicating with one end thereof for heating said hood, an elongated operating arm generally parallel to said hood and having one end fixed to the free end of said hood, said arm being relatively unaffected by the heat of said pilot means, said arm and said hood being substantially straight in both heated and cooled condition, an electrical switch operable by movement of the order of a few thousandths of an inch and having an operator adjacent the other end of said arm adapted to be operated by

said arm responsive to elongation and contraction of said hood under influence of said pilot means, said hood and arm having closely similar coefficients of expansion and being of approximately equal length, and the fixed end of said hood and said switch being mounted on a common bracket means, whereby a fine control of switch operation responsive to said pilot means is provided at all ambient temperatures.
